UNITED STATES PATENT OFFICE.

LEOPOLD WERNER, OF NEWARK, NEW JERSEY.

BELT-FASTENER.

SPECIFICATION forming part of Letters Patent No. 372,732, dated November 8, 1887.

Application filed December 28, 1886. Serial No. 222,769. (No model.)

To all whom it may concern:

Be it known that I, LEOPOLD WERNER, a citizen of the United States, residing at Newark, in the county of Essex and State of New Jersey, have invented certain new and useful Improvements in Belt-Fasteners; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide an improved belt-fastener that will secure the belt at any desired point and hold it firmly; also to provide a durable, convenient, and ornamental fastener, and to reduce the cost of manufacture.

The invention consists in an improved belt-fastener, and in the arrangements and combination of parts thereof, substantially as will be hereinafter set forth, and finally embodied in the clauses of the claims.

Referring to the accompanying drawings, in which like letters indicate corresponding parts in each of the several figures, Figure 1 is a front view of a lady's belt provided with my improved fastener. Fig. 2 is a section through line X, Fig. 1; and Fig. 3 is a section through line Y, same figure; and Figs. 4, 5, and 6 are details of modified forms of my fastener, which will be hereinafter more fully described. Figs. 7 and 8 are plan and side elevations, respectively, of a preferred construction; and Fig. 9 is a section through line Z, Fig. 7.

In said drawings, A represents a lady's belt, and B my improved fastener. One end of the belt A is immovably secured to an under plate, C, of said fastener by means of rivets, as D, or in any other suitable manner. Said rivets may also serve to secure an upper plate, E, to said lower plate, C, as in Fig. 3, the upper plate, E, being bent, as at F and G, so as to pass beneath the plate C and receive said rivets D. The sides of the upper plate, E, formed by bending, as above described, depend sufficiently from the body of said upper plate, E, as to provide a strap-opening, I, between the plate E and the plate C, adapted to receive the free end of the belt, which is designed to fit loosely therein.

A cylinder or sleeve, J, may be, and preferably is, secured at or near the center of the plate E, and is adapted to receive a post or bar, K. Said sleeve is slotted, as at L, Figs. 2 and 3, said slot being pitched similar to a screw-thread and adapted to receive a projecting lug, as M, which is formed on or secured to the post or rod K, at or near right angles thereto. Thus, when said post is turned laterally, the projecting lug M, working in the slot L, causes the post or rod K to move longitudinally, as will be understood. Said post or rod K is provided at one end with a pivotally-arranged serrated or roughened clamping-foot, as N, to engage the free end of the belt without turning pivotally thereon when forced downwardly by said post or rod K, to hold said free end of the belt firmly and securely and to prevent its withdrawal from the belt-opening I. To the opposite extremity of said post K is secured a suitable finger-piece, O, which may be milled on the edge to facilitate turning it, and may be engraved or otherwise ornamented on the top thereof. Said post may be also provided with a spring, as P, which may pass around the outside of the cylinder or sleeve J and engage the projecting lug M at one end, said lug extending sufficiently from the sleeve to receive it, and may engage at the opposite end the top of a cover or ornamental cap, Q. Said cap or cover Q serves to conceal the working parts and to keep them free from dust and dirt, and gives a finished appearance to the fastener. It may be secured to the top of the plate E in any suitable manner, but preferably by soldering or riveting, as at R, and may be engraved or otherwise decorated to give an ornamental appearance.

In lieu of the device above described for forcing the rod or shaft K downward, said rod may be provided with a screw-thread corresponding with a thread cut in said sleeve, as shown in Fig. 4; or a lever, as S, hook, as T, and cover, as Q, Fig. 5, may be used. In the latter case the lever S may be suitably fulcrumed, as U, to the plate E, and provided with a projection, V, to engage the top of the rod or shaft K, the latter being provided with a small flange, W, on the top to engage the spring P. When the said lever is pressed downward, the end may be inserted under the hook T, thus holding it firmly in place, and when released

the said spring P acts to carry it upward, thus unfastening the belt, as will be manifest. The movement of said arm is preferably limited by a slot, Q', in the cover Q, which slot may also 5 be provided with a shoulder, as T', to act in lieu of the catch T, as will be understood.

The preferred construction is shown in Figs. 7, 8, and 9, where the finger-piece and cover are integral and lengthened, or have projections O', which act as levers and also give an ornamental appearance to the fastener. Said levers may be provided with ornamental ball 10 projections, which present a convenient form for the fingers, and also, being at a distance 15 from the center, give increased power, as will be readily understood.

It is evident that other changes may be made in the form and proportion of parts herein shown without in any way departing from the 20 spirit and scope of my invention.

Having thus fully described my invention, what I claim as new is—

1. The combination, in a belt-fastener, with

plates C E, adapted to receive the free end of the belt, of a post or stud provided with a 25 foot having a pivotal relation to said stud, and means, substantially as described, to cause said foot to pass to and from holding contact with said belt, substantially as and for the purposes set forth.

2. The combination, in a belt-fastener, of a plate, E, a sleeve provided with an inclined slot, a post working in said sleeve and provided with a lug, M, and post N, and a finger-piece, O, a spring, P, and an abutment to engage said spring, all said parts being arranged and adapted to operate substantially as and for the purposes set forth.

In testimony that I claim the foregoing I have hereunto set my hand this 4th day of December, 1886.

LEOPOLD WERNER.
